OTHER PUBLICATIONS

European Patent Application No. 20173523, Partial European Search Report, dated Oct. 13, 2020.

Primary Examiner — Joshua Kading*Assistant Examiner* — Ieisha N Price(74) *Attorney, Agent, or Firm* — Marshall, Gerstein & Borun LLP(57) **CLAIM**

The ornamental design for a “coupling,” as shown and described.

DESCRIPTION

FIG. 1 is a rear perspective view of the coupling;
 FIG. 2 is a left-side view of the coupling of FIG. 1;
 FIG. 3 is a right-side view of the coupling of FIG. 1;
 FIG. 4 is front view of the coupling of FIG. 1;
 FIG. 5 is a rear view of the coupling of FIG. 1;
 FIG. 6 is a top view of the coupling of FIG. 1;
 FIG. 7 is a bottom view of the coupling of FIG. 1; and,
 FIG. 8 is a front perspective view of the coupling of FIG. 1. The broken lines in the drawings illustrate portions of the coupling and form no part of the claimed design.

1 Claim, 8 Drawing Sheets(56)
